UNITED STATES PATENT OFFICE.

MARIS JOSEPH GOEBEL, OF ALTON, IOWA.

RULER.

Application filed September 28, 1922. Serial No. 591,090.

To all whom it may concern:

Be it known that I, MARIS J. GOEBEL, a citizen of the United States, and a resident of Alton, in the county of Sioux and State 5 of Iowa, have invented certain new and useful Improvements in Rulers, of which the following is a specification.

My present invention provides a very simple and improved yet stable ruler which 10 may be used either as a lineal scale or as a straight edge for ruling with pen or pencil.

Furthermore, the invention provides a device of this class adapted for use as a paper cutter and so constructed that when placed 15 over freshly-inked lines or characters the likelihood of blotting is considerably reduced.

These and other objects and advantages I 20 successfully attain in the embodiment hereinafter described, defined in the appended claims and illustrated in the accompanying drawings, which form a part of this application and in which like characters of reference indicate corresponding parts throughout the several views, of which,—

Fig. 1 is a plan of the preferred embodiment of my device.

Fig. 2 is a transverse section thereof taken on the line 2—2 of Fig. 1.

Fig. 3 is a reverse plan of the device as applied in cutting paper, and

Fig. 4 is an end elevation of the same.

Referring, now, to the illustrations the device consists of an elongated sheet metal strip having its side edge portion bent to provide a flange, 5, disposed at an acute angle to the intermediate portion, 6, the other side edge portion, 7, being bent at a slight angle to the plane of the intermediate 35 portion, 6, the extreme edge of the portion, 7, being preferably beveled to a sharp edge, as at 8. The flange, 5, is preferably folded upon itself, as at 9. As clearly shown in Fig. 2, the flange, 5, and portion, 7, are so related that the flange, 5, will be vertically disposed when the ruler rests with its flange and edge, 8, on a horizontal surface. In this position the face of flange, 5, may be used as a straight edge for ruling with 45 either a pen or pencil. Either or both sides of the ruler may be provided with graduated scales, 10. Adjacent its flanged edge and on the side thereof opposite the flange the ruler is provided with projecting studs, 11, so that when the ruler is inverted, as 50 shown in Figs. 3 and 4, the ruler rests upon

the studs, 11, and the beveled edge, 8, in which position the ruler may be placed over freshly inked lines or characters without blotting, and the angle or point of juncture 60 of the flange, 5, and immediate portion, 6, may be used as a straight edge for ruling with pen or pencil. Also, when held in this position on a sheet of paper, as clearly shown in Figs. 3 and 4, the paper may be 65 accurately torn or cut by the beveled edge, 8, by pulling upwardly on the portion of the paper exposed at the edge of the ruler. It will also be observed that when using the ruler for this purpose very little pressure is 70 required upon the ruler, as with a light pressure the studs, 11, will prevent relative movement between the ruler and paper while the latter is being cut.

Having thus described my invention, what 75 I claim as new and desire to secure by Letters Patent of the United States, is,—

1. A ruler consisting of an elongated plate formed with flanged and unflanged ruling edges and a flat intermediate portion interconnecting the two edges, the flanged edge portion being disposed at an acute angle to the intermediate portion.

2. A ruler consisting of an elongated plate formed with flanged and unflanged ruling edges and a flat intermediate portion interconnecting the two edges, the flanged edge portion being disposed at an acute angle to the intermediate portion, and the unflanged edge and the edge of the flange being disposed in a common plane at right angles to the plane of the flange.

3. A ruler consisting of an elongated plate formed with flanged and unflanged ruling edges and an intermediate portion interconnecting the two edges, and a longitudinal series of spaced studs projecting from the face of the intermediate portion opposite from the flange.

4. A ruler consisting of an elongated plate formed with flanged and unflanged ruling edges and a flat intermediate portion interconnecting the two edges, the flanged edge portion being disposed at an acute angle to the intermediate portion, and the unflanged edge and the edge of the flange being disposed in a common plane at right angles to the plane of the flange, and a longitudinal series of spaced studs projecting from the face of the intermediate portion opposite from the flange.

5. A ruler consisting of an elongated plate

2
formed with flanged and unflanged ruling edges and an intermediate portion interconnecting the edges, the flange being disposed at an acute angle to the intermediate portion, and the unflanged edge portion being bent at an obtuse angle to the face of the intermediate portion opposite from the flange.

6. A ruler consisting of an elongated plate formed with flanged and unflanged ruling edges and an intermediate portion interconnecting the edges, the flange being disposed at an acute angle to the intermediate portion, and the unflanged edge portion being bent at an obtuse angle to the face of the intermediate portion opposite from the flange, and a longitudinal series of spaced

studs projecting from the face of the intermediate portion opposite from the flange.

7. A ruler consisting of an elongated plate 20 formed with flanged and unflanged ruling edges and an intermediate portion interconnecting the edges, the flange being disposed at an acute angle to the intermediate portion, and the unflanged edge portion being bent 25 at an obtuse angle to the face of the intermediate portion opposite from the flange, and a longitudinal series of spaced studs 30 projecting from the face of the intermediate portion opposite from the flange, and positioned adjacent to the flanged edge.

In testimony whereof, I have hereunto set my hand this 23rd day of September, 1922.

MARIS JOSEPH GOEBEL.
